UNITED STATES PATENT OFFICE.

FRANK D. LINGENFELTER, OF SYRACUSE, NEW YORK, AND WILLIAM E. CUTTS, OF WYNCOTE, WYOMING.

RUNNING-GEAR.

No. 915,101.

Specification of Letters Patent. Patented March 16, 1909.

Application filed February 29, 1908. Serial No. 418,570.

To all whom it may concern:

Be it known that we, FRANK D. LINGENFELTER and WILLIAM E. CUTTS, citizens of the United States, residing, respectively, at 5 Syracuse and Wyncote, in the counties of Onondaga and Laramie, States of New York and Wyoming, have invented a new and useful Running-Gear, of which the following is a specification.

10 This invention relates to running gear for vehicles, and has for its object to provide an improved means for connecting the fifth wheel with the reach, whereby a flexible connection shall be established which will enable 15 the front or steering axle to be rocked or tilted while passing over rough roads without straining the parts of the running gear.

Another object of this invention is to do away with bolts, that is, in so far as employing 20 the latter for retaining the various parts in working position.

It is well known that in most devices of this kind, draw-bolts are used for connecting the fifth wheel with the axle and reaches.

25 This construction has many disadvantages, chief among which is that as the parts are worn through use and the connections become loose, rattling results. Various attempts have been made to overcome this defect, and 30 in most of the appliances now in use the connections are made rigid. The disadvantage of this construction is that the parts will break when passing over rough ground if no allowance is made for play, and when such 35 allowance is made the parts will rattle.

The present invention aims to remedy this defect by employing a swivel connection between the rear and front axles, thereby permitting the axles to rock on the connection when passing over uneven roads and 40 instead of using the usual draw bolts for connecting the parts, thimbles are employed, the latter forming a tight but yielding connection. Thus the danger of breakdown caused 45 by bolts working loose is avoided since the thimbles are preferably formed integral with their respective parts, whereby the wear on the parts may be taken up, thus positively preventing rattling.

50 With these and other objects in view, as will more fully hereinafter appear, the invention consists in certain novel features of construction and arrangement of parts, herein- 55 after fully described, illustrated in the accompanying drawings, and particularly pointed

out in the appended claims, it being understood that various changes in the form, proportions, size and minor details of the structure may be made without departing from the spirit or sacrificing any of the advantages 60 of the invention.

In the accompanying drawings:—Figure 1 is a perspective view showing the device attached to the front axle of a wagon and the connection with the front end of the reach 65 bar. Fig. 2 is a longitudinal sectional view of Fig. 1: Fig. 3 is a view of the collar used for taking up the wear of the spindle.

Similar numerals of reference are employed to indicate corresponding parts throughout 70 the several figures of the drawings.

The axle 1 of the ordinary type has disposed on its lower face a plate 2 provided on either side and at the ends with perforated lugs 3 and a central lug 4. A similar plate 5, 75 but of greater length than the plate 2, is disposed on the upper face of the axle, and at either end is provided with segments 6, the upper faces of which are flat and the lower faces provided with recesses 7, which form 80 seats for the axle 1. Centrally disposed on the plate 5 is a socket 9 which registers with the lug 4 on the lower plate 2. The fifth wheel 8 in the present instance is a circular member, the lower face of which is flat and 85 bears on the upper faces of the segments 6, and is provided with a diametrically cross bar 10, the ends of which are secured in recesses 11 on the upper face of the fifth wheel which form seats for the head block 12 of the 90 vehicle. Extending at right angles to the cross bar 10 is a radial bar 13 which serves to strengthen the fifth wheel, and on its lower face a thimble 14 adapted to enter the socket 9. The latter is connected to the lug 4 by 95 means of a long thimble or sleeve 15 having a shoulder formed on the lower end which rests on the upper face of the lug 4, the reduced end projecting through the perforation in the lug and forming a shaft over which fits one end of 100 a brace 16, the opposite end of which is secured to a thimble 17 formed on the lower face of the wheel 8, and diametrically opposite the socket 9 and thimble 14. With this construction it is obvious that the connection 105 between the wheel and axle is made by the thimbles, the function of the bolt 18, extending from the upper face of the radial bar through the thimble 14 and sleeve 15, being merely to tighten the joints in the 110

socket 9 and keep the lower end of the brace 16 in close contact with the shoulder of the thimble 15. The advantages thus gained positively prevent rattling, since there is 5 absolutely no pulling on the draw-bolt 18 and bolt 19. In fact, if either of these bolts work loose and were lost, it would not interfere with the progress of the vehicle.

Formed integral with, or otherwise secured 10 to the radial bar 13, is a bar or member 20 extending rearwardly and terminating directly behind the circle of the fifth wheel in a spindle 21 provided at its outer end with an annular flange or head 22. The reach, 15 which in Fig. 1 has been shown as composed of forwardly converging bars 23, supports at its front end 24 two flanged side members 25 engaging the reach members 23 with which they are connected by screws or bolts, 20 whereby the reach members are firmly secured in proper position with relation to each other. The casting 24 includes a box or bearing, the lower plate of which is provided with a central groove 26 and the upper plate with a 25 similar groove 27, forming a bearing for the spindle 21, the head 22 of which abuts on the head of the bearing box. Disposed between the plates of the bearing box, and on either side of the grooves, is packing, thus 30 rendering it possible at all times to take up any wear on the spindle 21 caused by rocking, the member 28 having on one end depending flanges, and provided with an elongated slot 29 for the reception of the bolt 19 35 to secure it to the wheel 8. The opposite end of this member is adapted to overlie the spindle and contact with the forward end of the bearing box. The function of this member or collar, bearing as it does at all times on 40 the end of the box, is to take up the wear of the spindle head 22.

The advantages of the swivel construction are readily seen when compared with most devices of this kind, where the reach is con-

nected to the forward axle. With the swivel 45 the connections can be adjusted to give the parts ample play when under strain, and at the same time prevent rattling.

What is claimed is:—

1. A running gear embodying a fifth wheel 50 provided with a radial bar terminating in a spindle projecting beyond the periphery of said fifth wheel, reach bars carrying a box provided with a longitudinal groove for the reception of the spindle, and an adjusting 55 collar embracing said spindle and interposed between said fifth wheel and one end of said box.

2. A running gear embodying reach bars, having at one end a box provided with a 60 longitudinal groove, a fifth wheel, a spindle secured to said fifth wheel, having a portion projecting beyond the periphery thereof and adapted to enter said grooved box, and an 65 adjusting member carried by said fifth wheel having a circular portion adapted to embrace said spindle and disposed between said fifth wheel and one end of said box.

3. A running gear for vehicles embodying 70 an axle member having plates secured to the upper and lower faces thereof; lugs having alining openings formed on said plates; a fifth wheel having a radial bar with thimbles on the lower face and at the opposed ends thereof, one of said thimbles adapted to enter the opening in the lug on the upper plate; a sleeve connecting said thimble with the lower of said lugs and a strut bar connecting the other thimble of the radial bar with the 75 sleeve.

In testimony that we claim the foregoing as our own, we have hereto affixed our signatures in the presence of two witnesses.

FRANK D. LINGENFELTER.
WILLIAM E. CUTTS.
